Application June 14, 1954, Serial No. 30,955

Term of patent 14 years

(Cl. D65—1)

To all whom it may concern:

Be it known that we, Robert M. Wagner, Richard L. Swart, and Fred Victory, citizens of the United States, residing in the cities of Rochester, Royal Oak, and Roseville, respectively, counties of Oakland, Oakland, and Macomb and State of Michigan, respectively, have invented a new, original, and ornamental Design for a Food Pump Unit, of which the following is a specification, reference being had to the accompanying drawing, forming part thereof, in which:

Fig. 1 is a perspective view from the front and side of a food pump unit showing our new design;

Fig. 2 is a perspective view similar to Fig. 1 but showing the cover portion in its open position; and

Fig. 3 is a perspective view from the rear and other side.

We claim:

The ornamental design for a food pump unit, substantially as shown.
